UNITED STATES PATENT OFFICE.

PERCY C. RODWELL, OF ORANGEBURG, SOUTH CAROLINA.

UNDERGARMENT.

Application filed December 22, 1925. Serial No. 77,074.

This invention relates to improvements in undergarments and has for an object the provision of means for reinforcing the elastic connecting band commonly found in athletic union suits, the purpose being to strengthen and reinforce the garment without interfering with freedom of movement.

With the above and other objects in view, the invention provides a novel arrangement 10 of reinforcing strips which act to gradually resist stretching, resistance of the strips increasing with increased stretching action of the wearer, so that stretching will not be suddenly checked, but will be checked gradually and danger of injury to the garment will be materially reduced.

Another object of the invention is to so dispose the reinforcing strips as to distribute the strain over a relatively large area and 20 further to provide direct resistance to lateral strains.

With the above and other objects in view, the invention further includes the following 25 novel features and details of construction, to be hereinafter more fully described, illustrated in the accompanying drawings and pointed out in the appended claim.

In the drawings:—

Figure 1 is a perspective view of a garment with the invention included.

Figure 2 is an enlarged fragmentary elevation showing the arrangement of the reinforcing strips.

Referring to the drawings in detail where- 35 in like characters of reference denote cor- responding parts, the garment which is of the type commonly referred to as an athletic union suit, includes an upper or body portion 10 and a lower or nether portion 11, 40 the said portions being connected by a strip 12 of suitable elastic material, the wales of the strip extending longitudinally thereof, or transversely of the garment.

The invention comprises reinforcing strips 45 13 which are also formed of suitable elastic material and which have their wales extending longitudinally. The strips 13 are crossed so as to form the letter X and are connected at their crossed portions as indicated at 14.

50 The opposite ends of the strips are suitably

connected to the adjacent edges 15 of the upper and lower portions 10 and 11 of the garment.

By reference to Figure 2 of the drawings it will be seen that the wales of the reinforcing strips 13 extend diagonally of the wales of the connecting strip 12 and when the latter is stretched, strain will be transferred from the strips 13, these strips, due to their arrangement and disposition, will gradually take up the strain and resist separating movement between the adjacent edges of the upper and lower portions of the garment. This gradual checking action will act to minimize the danger of tearing or 65 separating the connected portions of the garment and is in contradistinction to the sudden stopping action where reinforcing strips are arranged at right angles to the waistline. Further, the arrangement of the 70 strips provides for a gradual checking of the stretching action of the connecting strip when this action is occasioned by sidewise movement of the body of the wearer, or movement of only one shoulder.

The invention is susceptible of various changes in its form, proportions and minor details of construction and the right is herein reserved to make such changes as properly fall within the scope of the appended 75 claim.

Having described the invention what is claimed is:—

In combination with a garment includ- 85 ing upper and lower members and an elastic strip connecting said members, said strip having its wales extending substantially parallel with the adjacent edges of the upper and lower members, diagonally disposed crossed reinforcing strips having their op- 90 posite ends secured to the adjacent edges of said upper and lower members and their wales extending longitudinally with respect to said diagonal strips and diagonally dis- 95 posed with respect to the wales of the elastic connecting strip with the crossed portions of said reinforcing strips secured together.

In testimony whereof I affix my signature.

PERCY C. RODWELL.
